CLAIM

The ornamental design for a kiosk, as shown and described.

DESCRIPTION

FIG. 1 is a top, front and right perspective view of a kiosk showing my new design;

FIG. 2 is a top view of the design shown in FIG. 1;

FIG. 3 is a bottom view of the design shown in FIG. 1;

FIG. 4 is a left side view of the design shown in FIG. 1;

FIG. 5 is a right side view of the design shown in FIG. 1;

FIG. 6 is a front view of the design shown in FIG. 1; and,

FIG. 7 is a rear view of the design shown in FIG. 1.

The broken lines depict portions of the kiosk which form no part of the claimed design.
